P. Daniel

Motor.

Nº 20,701.

Patented June 29, 1858.

Fig: 1.

Fig. 2.

UNITED STATES PATENT OFFICE.

P. DANIEL, DECEASED, OF FRANKLIN COUNTY, KENTUCKY; JNO. F. DUNNINGTON,
ADMINISTRATOR.

MODE OF OBTAINING MOTIVE POWER.

Specification of Letters Patent No. 20,701, dated June 29, 1858.

To all whom it may concern:

Be it known that I, PETER DANIEL, of Franklin county, Kentucky, have invented certain new and useful Improvements in 5 Mode of Generating Motive Power; and I do hereby declare that the following is a full, clear, and exact description of the same, reference being had to the accompanying drawings and to the letters of reference 10 marked thereon.

The nature of my invention consists in the arrangement of certain devices the peculiarities of which will be hereinafter fully described.

15 In order that others skilled in the arts may manufacture and use my machine I will proceed to describe its construction and operation.

In the accompanying drawings making 20 a part of this specification Figure 1 is a plan view. Fig. 2 is a side elevation.

In Fig. 1, A is the frame of the machine, A' and A'' are horizontal shafts secured in this frame. 1 and 2 are large pulleys secured to shaft A' and 3, is a large cog wheel secured to the same shaft. 5 is a large cog wheel secured to shaft A'', and 6, and 7, are large pulleys secured to said shaft, all being located in the relative positions seen 25 in the drawings. S, and S' are horizontal shafts secured to the frame A, in a position above the shafts A', and A''. K, is a pulley secured to shaft S, and K' is a pulley in like manner secured to shaft S', K, being 30 directly above pulley 1, and K' being directly over pulley 6. 4, is a cog wheel of smaller dimension secured in a position between wheel 3, and wheel 5. This cog wheel has an adjustable bearing by means of which 35 it may be moved in gear or out of gear with the two wheels 3, and 5. L, is a shaft connecting with wheel 4, and which serves to convey power from the machine to any desired point. (i) is a lever to which is secured the cord J, said lever being attached 40 to the adjustable piece in which 4, has its bearing, 4 being thrown in or out of gear by means of this cord and lever. (d d) is a railroad, said road being poised on the 45 center shaft d'. (e e) is a railroad also poised on center shaft e'. 6, and e, are pulleys around which cords pass for the purpose of operating the rail roads as will be described. (a) is a pulley around which 50 cord J, passes.

In Fig. 2, it will be seen that A is the frame of the machine. 3, 4, and 5, are the cog wheels seen and described in Fig. 1, 4, being the center wheel which has its bearing in the adjustable piece G. F, is 60 a cord one end of which is secured to the car E, the other passing around pulley 2, is secured to it. There is also a cord, one end being secured to a corresponding car, the other in like manner passing over pulley 65 7, is secured to it. F', is a cord secured at one end to pulley 1, the other end passing up over the pulley K, has a weight o secured to it, h, is a cord one end being secured to pulley 6 and the other passing over pulley K' has also a weight O', secured to it. B and B', are levers which have their 70 bearings or fulcrums at x, x, the short ends of these levers being secured respectively to the two ends of the rail road e by means of the cords c', c'. C, is a cord one end of which is secured to the outer extremity of lever B, passes around pulley P', and up to and around the wheel M, down and around pulley f, and is secured to the extremity 75 of the long arm of lever B'. D, and D', are uprights in which the levers B, and B' have their fulcrums, or bearings. (i) is a lever secured to the adjustable piece G, and operated by means of the cord J, Fig. 1, 80 85 for the purpose of operating said piece G, and throwing wheels 3 and 5, in or out of gear with wheel 4.

In the operation of this machine we will suppose that o' is wound up and is running 90 the machinery connected to shaft L, Fig. 1. Now while this weight is running down I am winding up weight O, in the following manner. The car E, being heavily freighted, is made to run on the railroad, e, now this railroad working on a movable or fixed center it will be seen that when the wheel M, is turned in one direction the railroad will be tilted up, and the car will run down an inclined plane, and thus draw up the weight. The 100 car is freighted sufficiently to draw up the weight before the other weight o' runs down. When the weight o' runs down and I wish to set the other weight at work, I throw the wheel 4 in gear with wheel 3 by means of 105 lever, i, and then by turning the wheel M, in an opposite direction, the car run off to the other end of the track and relieves the weight of its power. The power of the weight is then free to act on the machinery 110

attached to the shaft L. While this weight is running down the other weight is wound up in the same manner by means of the car on the other track, and as soon as this is 5 wound up, and the other runs down, I throw wheel 4, in gear with wheel 5, by means of lever, i, then tilt the railroad up to relieve the weight and thus the machinery is kept constantly in motion.

- 10 I may find it convenient to have a catch for the purpose of stationing the shafts S and S', Fig. 1, in order to keep the weight suspended while the railroad is being tilted back for the car to relieve the weight of its 15 power. This catch will suspend the weight until the other weight runs down and then this side of the machine being thrown in gear, the catch is removed and the machinery moves on without any stoppage.
- 20 It will be seen that the wheel 4, being placed between two wheels, which run in opposite directions, that when in gear with first one and then the other of these wheels it always runs in one direction, thus giving the 25 machinery when in operation only a forward motion.

The advantage to be derived from this machine is that one person, stationed at the wheel M, may tilt up the railroad by means 30 of the very great lever power here employed so that the cars may run down and wind up the weights, the same person may operate the lever, i, and thus throw the wheels in and out of gear as may be required, by one 35 weight running down and attaching the other. It will not be necessary to raise the

end of the railroad much in order to have the car start down toward the other end and thus commence the operation of drawing up the weights. If my weights o, and o' weigh 40 1,000 lbs. apiece it may be necessary to make the cars weigh 5,000 or 6,000, lbs. apiece in order to draw them up and as my leverage is very great, I may use double that weight and still have the machine operated by one 45 man. I may have the ends of my railroads to rest on movable timbers when the road is level and then have a rolling center which may be placed very near to one end of the track when the car is stationed and then as 50 soon as it starts down it will bear the road down by its own weight without the necessity of the man's turning the wheel M, more than once around. I may vary my forms and machinery some not confining myself 55 to the exact description as herein found.

Having thus fully described my invention what I claim as new and desire to secure by Letters Patent is—

The arrangement of pulleys 1, 2, 6, 7, 60 wheels, 3, 4, 5, lever, i, belt or cord J, shafts S, and S', and pulleys k, k', with the cords, F, F', weights o, o', car E, railroad e, and the lever, B, B', pulleys P', and f, cord C, and wheel M, when all are operated in the 65 manner herein set forth and for the purpose described.

PETER DANIEL.
